UNITED STATES PATENT OFFICE

2,140,273

GIRDLE

Max Simon, New York, N. Y., assignor to I. B.
Kleinert Rubber Company, New York, N. Y., a
corporation of New York

Application September 10, 1937, Serial No. 163,230

2 Claims. (Cl. 2-37)

This invention relates to wearing apparel and more particularly to foundation garments such as girdles.

Girdles are customarily constructed in whole or in part of elastic material such as knit fabric including elastic threads arranged in the fabric and disposed in the girdle so that the latter possesses substantial elasticity circumferentially of the wearer and also limited stretch longitudinally of the wearer by reason of the knit formation of the fabric. In girdles constructed of such elastic material and provided with an upper front portion which projects above the waist-line in position to overlie the wearer's diaphragm for preventing bulging of the latter, difficulty has been experienced in attaching the edge binding to said projecting portion of the girdle due to the loose ends of the textile and elastic threads at said edge of the projecting portion of the girdle. In other words, when the edge binding is stitched directly to the edges of the projecting portion of the girdle, the securement of the edge binding is defective and unsatisfactory and frequently said edge binding separates from said edge of the girdle portion or is pulled away by the force exerted on the shoulder straps which are attached to or adjacent said binding in girdles of this type. It is therefore an object of the present invention to eliminate this difficulty and for that purpose to provide the edge of the projecting portion of the girdle with means serving to securely anchor the stitches by which the edge binding is attached.

It is also an object of the invention to provide a girdle of the character described composed of two-way stretch material and provided with an upwardly projecting portion arranged to overlie the wearer's diaphragm and provided with shoulder straps for holding said portion of the girdle in place and to prevent the upper edge of the girdle from rolling downwardly.

The above objects of the invention and other objects which might hereinafter appear will best be understood from the following description considered with reference to the accompanying drawing.

In the drawing:

Fig. 1 is a front view of a girdle embodying the present invention;
Fig. 2 is a fragmentary plan view, on an enlarged scale, of the upwardly projecting part of the girdle before the attachment of the edge binding;

Fig. 3 is a view similar to Fig. 2 showing the edge binding attached.

Referring now more particularly to the drawing, the girdle 10 made in accordance with the present invention comprises a body portion 12 composed of knit fabric containing textile threads and elastic threads interknit therewith and extending circumferentially of the girdle as indicated more or less diagrammatically by the transversely extending lines 14. Due to the construction of the fabric said girdle has substantial elasticity circumferentially of the wearer and has limited elasticity longitudinally of the wear, whereby the girdle is of the type known as a two-way stretch girdle. Said girdle may be formed from flat knit material or as here shown from tubular knit material whereby the body portion 12 is circumferentially continuous thereby obviating the necessity for a seam for securing the ends of the body portion.

In accordance with the present invention girdle 10 is also provided with an upwardly projecting portion 16 integral with body portion 12 and extending above the normal waist-line of the girdle for overlying the wearer's diaphragm to prevent bulging of the latter. Said extended portion is defined by upwardly converging edges and is of progressively decreasing width toward said edges. Said portion is formed by cutting the same from the material in integral relation to the material forming body portion 12. The unbound edges of said projecting portion are thus cut edges. An elastic edge binding 18 is secured continuously around the upper edge of the girdle, and a similar elastic edge binding 20 is secured to the lower edge of the girdle continuously therearound whereby said edges are circumferentially elastic together with the edge portions of the girdle to which they are attached. Adjustable shoulder straps 22 and 24 are stitched at their ends to the pointed end portion of projection 16 at the front of the girdle and to spaced points at the back of the girdle at the upper edge thereof.

As previously indicated when the edge binding 18 is stitched directly to the material of projecting portion 16, attachment of the edge binding is insecure, principally because of the cut edges of said portion, with the result that said edge binding is frequently pulled away and separated from the material of said projecting portion and it is also difficult to properly attach the ends of the shoulder straps to the girdle. In order to obviate this difficulty provision is made for securely holding the threads 26 (Fig. 3) by which edge binding 18 is attached. This is accomplished in accordance with the present invention, as illustrated in Fig. 2, by stitching

- through the marginal edge portion 28 of projecting portion 16 for the full length of said projecting portion at the cut edges thereof, that is from a point A just rearwardly of one side of the girdle to a point B just rearwardly of the other side of the girdle. The stitching utilized for this purpose, as indicated by the reference numeral 30, in Fig. 2, is done on a machine known as a Wilcox and Gibbs flat lock, four needle machine.
- 10 As stitching of this character is well known to those skilled in the art further illustration or description thereof is considered unnecessary. As here shown said stitching comprises a plurality of interlocked threads which pass through the marginal edge portion of projecting part 16 of the girdle thereby securing together the ends of the knit threads of the girdle material, including the elastic threads and thereby holding them in place. Said stitching 30 is disposed over a marginal surface area corresponding in width substantially to the width of the folded portions 32 of edge binding 18 on both surfaces of said projecting portion thus not only interconnecting the threads of the knit fabric but also reinforcing the marginal edge portion of the knit material and providing thread portions on both surfaces of said marginal edge portion for interengagement with stitching 26 by which the edge binding is attached. In this manner a secure attachment between the edge binding and the edge of projecting portion 16 is obtained whereby to prevent said edge binding from being pulled off or otherwise separating from said projecting portion.
- While stitching 30 is normally inelastic, the edges of portion 16 provided with said stitching possess sufficient elasticity by reason of the bias cut of the material of said projecting portion. In order, however, to prevent stitching 30 from interfering with the elasticity of the upper rear edge portion of the girdle, said stitching terminates substantially at the sides of the girdle as previously described with reference to points A and B indicated in Fig. 1, stitching of said rear upper edge portion of the girdle being unnecessary as the material of the girdle at said edge portion is continuous together with the remaining part of the body portion 12 of the girdle, and the continuous knit material at said rear upper

edge portion provides sufficient anchorage for edge binding 18.

Thus it is seen that the construction herein shown and described is well adapted to accomplish the several objects of the invention. It will be understood, however, that while the girdle constructed as here shown constitutes the preferred embodiment of the invention, certain changes in the construction and arrangement of parts and in the form of the girdle may be made without departing from the scope and spirit of the invention. Accordingly, I do not wish to be limited precisely to the present construction except as may be required by the appended claims considered with reference to the prior art.

Having described my invention what I claim and desire to secure by Letters Patent is:

1. A girdle comprising a body encircling portion comprising knit fabric which possesses substantial elasticity circumferentially of the wearer and limited stretch longitudinally of the wearer, a portion integral with and extended from the upper part of said body portion at the front of the girdle and of progressively decreasing width toward its outer edge, a plurality of threads 25 stitched through the marginal edge of said extended portion, said threads terminating substantially at the sides of the girdle and an edge binding folded over said stitched marginal edge on both surfaces thereof and stitched thereto inwardly of the edges of said extended portion.

2. A girdle comprising a body encircling portion comprising circumferentially endless tubular knit fabric which possesses substantial elasticity circumferentially of the wearer and limited stretch longitudinally of the wearer, a portion integral with said body portion and extended upwardly therefrom, said extended portion having upwardly converging bias cut edges, means for securing the threads of said extended portion at 40 said cut edges comprising additional threads stitched through a marginal edge of said extended portion, said threads terminating substantially at the sides of the girdle, and an elastic edge binding stitched by additional threads to 45 said marginal edge of the extended portion inwardly of said bias-cut edges thereof.

MAX SIMON.
